ALKYLATION OF PARAFFINS

Frederick E. Frey, Bartlesville, Okla., assignor to
 Phillips Petroleum Company, a corporation of
 Delaware

Application January 8, 1940, Serial No. 312,964

11 Claims. (Cl. 260—683.4)

1

This invention relates to the alkylation of paraffins, and more particularly to the alkylation of paraffins by alkyl halides.

I have found that alkylation of paraffins by alkyl halides may be effected efficiently in the presence of concentrated sulfuric acid at ordinary temperatures. I have also found that sulfuric acid containing a low concentration of aluminum sulfate as a promoter is a good catalyst for such alkylations. I have further found that the alkylation reaction is favored by the paraffin having a branched structure with a tertiary hydrogen, and by the alkyl group being non-primary, that is, secondary or tertiary. Furthermore, I have found that chlorides are somewhat more advantageous than other halides for the alkylation of paraffins.

An object of this invention is to effect the alkylation of paraffins to form paraffins having a higher molecular weight.

Another object is to effect alkylation of paraffins with alkyl halides.

Another object is to decrease the volatility of paraffins, especially of lower-boiling isoparaffins.

Another object is the production of isoparaffins having a desired and previously selected molecular structure.

Other objects and advantages of the invention will be obvious to those skilled in the art.

The invention will be readily understood from the following description and the accompanying drawing, which shows a flow-diagram for a preferred mode of operation adapted to produce hydrocarbons boiling in the motor-fuel range.

A feed stock comprising chiefly at least one paraffin enters the system through inlet 1 having control-valve 2. Another feed stock, comprising chiefly at least one alkyl halide enters the system through inlet 3 having control-valve 4. Either or both feed stocks may be added continuously or intermittently. The two feed stocks are intimately mixed with each other and with concentrated sulfuric acid in alkylator 5, as by vigorous mechanical stirring. The sulfuric acid, which enters alkylator 5 through inlet 6 having control-valve 7, may have a strength within the range 90 to 105 per cent by weight, preferably between 96 and 102 per cent. Under the influence of the sulfuric acid, the paraffins are alkylated by the alkyl halide, forming less volatile paraffins. The reaction temperature may be in the range 0 to 125° F., preferably about 70° F.

Various reactions occur in alkylator 5, but the primary reaction is believed to be alkylation of paraffins, especially isoparaffins, which are alkylated more easily than normal paraffins. The

2

primary alkylation product appears to undergo secondary reactions that form lower-boiling and higher-boiling products; it doubtless also undergoes isomerization.

5 The reaction appears to proceed most efficiently for isoparaffins, especially those having four to eight carbon atoms per molecule, and for non-primary alkyl halides in which the alkyl group has three to six carbon atoms. Of the non-primary alkyl halides, the tertiary react somewhat more rapidly than do the secondary; hence, if a secondary alkyl halide is used, it is advantageous to use a relatively high strength of acid, such as 100 to 105 per cent sulfuric acid.

10 Fluorides, chlorides, bromides, and iodides may be used, but bromides and especially iodides have a marked tendency to reduce the sulfuric acid, and for this reason, and for economic reasons, it is preferable to use the chlorides. The products formed when a propyl or butyl chloride is reacted with isobutane or isopentane boil chiefly in the gasoline range, are substantially completely saturated, and have excellent anti-knock ratings.

15 The reaction is favored by a high ratio of paraffin to alkyl halide; for this reason the alkyl halide advantageously may be added intermittently or portion-wise, as taught for olefins in the Frey Patents 2,002,394 and 2,104,296.

20 The reaction is also favored by a relatively high ratio of sulfuric acid to hydrocarbons; the acid preferably should have a volume within the range 0.1 to 2 times the volume of hydrocarbon, advantageously within the range of 0.5 to 1. If desired, the acid may contain a promoter, such as silver sulfate, aluminum sulfate, and the like, preferably in relatively low concentrations, such as from 0.5 to 5 per cent by weight.

25 Intimate contact between the sulfuric acid and the alkylation reactants is essential. This preferably is obtained by vigorous mechanical stirring or mixing and by the presence of an adequate amount of acid. It also may be promoted by the presence of certain emulsifiers in the mixture, such as, for example, alkyl sulfates. As alkyl sulfates or equivalent compounds are formed to some extent during the reaction, a small proportion of spent acid advantageously may be added to fresh acid to increase its ability to emulsify with the alkylation reactants.

30 Like all organic reactions, the alkylation of paraffins with alkyl halides requires some time to approach completion. Generally a reaction time between 5 minutes and 3 hours is adequate; much longer periods preferably should be avoided, as they favor secondary reactions that convert the

primary alkylation product into lower-boiling and higher-boiling products. Some indication of the progress of the reaction may be obtained from the rate of evolution of hydrogen halide, which is a by-product of the primary reaction; the hydrogen halide advantageously may be removed and used for the manufacture of additional alkyl halide.

After a suitable reaction time, the mixture of hydrocarbons, sulfuric acid, and by-products, such as hydrogen halide, is passed through valve 8 and conduit 9 into separating means 10, in which the sulfuric acid is separated from the mixture. The sulfuric acid may be withdrawn through valve 11 and outlet 12, and thence it may be subjected to a process of reclamation, if desired; or, alternatively, if may be returned, partly or entirely, as is desired or as trial indicates is desirable, to alkylator 5 through valve 13 and conduit 14. Hydrogen halide is withdrawn through valve 15 and outlet 16, and thence it may be used for the preparation of additional alkyl halide. The hydrocarbons are passed through valve 17 and conduit 18 to alkali treater 19, in which any acidic material is removed by a treatment with an alkali, detailed equipment for this being within the skill of one versed in the art, and not shown. Under some conditions of operation, a small amount of acidic material in the hydrocarbons may be tolerated; under such conditions, if desired, at least part of the hydrocarbon material from separating means 10 may be passed through valve 23 and conduits 24 and 21 directly to fractionating means 22 without being subjected to an alkali treatment in alkali treater 19.

From alkali treater 19 the hydrocarbons are passed through valve 20 and conduit 21 to fractionating means 22. In fractionating means 22, the hydrocarbon material is fractionated into a heavy-oil fraction, which is withdrawn through valve 25 and outlet 26; into a gasoline or motor-fuel fraction, which is withdrawn through valve 27 and outlet 28; and into a light-hydrocarbon fraction, which may be recycled to alkylator 5 through valve 29 and conduit 30, or may be discharged from the system, entirely or in part, through valve 33 and outlet 34. This light-hydrocarbon fraction comprises chiefly unreacted paraffins and, if desired when used as a recycle stock, the lower-boiling alkylation products, such as those containing up to about seven carbon atoms per molecule. If desired, a light-gas fraction comprising chiefly paraffins having less than four carbon atoms per molecule, which are alkylated less readily than heavier hydrocarbons, may be withdrawn through valve 31 and outlet 32. Unreacted alkyl halides may be removed through conduit 35 and valve 36, or may be recycled, entirely or in part, through conduit 37 and valve 38 to conduit 3.

It is to be understood, in connection with the foregoing process, that only the principal steps have been shown, and that mechanical details of each step will be somewhat dependent on each adaptation of my invention. The separating means and fractionating means shown will comprise separators, fractionators, pumps, tanks, cooling and heating units, etc., and similar equipment will also be required for the other steps shown. Such equipment is of common knowledge, and can be readily included by one skilled in the art.

The term isoparaffin as used in this specification, in connection with the charge stock, refers to paraffin hydrocarbons such as isobutane (2-methylpropane), isopentane (2-methylbutane),

and the like, that is, hydrocarbons which contain at least one tertiary hydrogen atom. Other examples of such hydrocarbons are the isohexanes 2- and 3-methylpentane, isoheptanes such as 2- and 3-methylhexane, 2,3- and 2,4-dimethylpentane, and 3-ethylpentane, and the like. The isoparaffins produced generally, although not necessarily always, will have a similar structure. When it is desired to produce a gasoline, or some certain valuable hydrocarbon or hydrocarbons boiling in the motor-fuel range, it will generally not be desirable to use an isoparaffin of higher molecular weight than isobutane or isopentane, or possibly an isohexane. When it is desired to produce higher-molecular-weight paraffins, correspondingly higher-molecular-weight initial paraffins should be used as the charge stock.

It has been found that the more highly branched isoparaffins of higher molecular weight are somewhat readily decomposed by prolonged contact with sulfuric acid, and when these are used the reaction conditions should be so modified, as indicated by trial, that extensive deleterious decomposition does not take place. For this reason, it may at times be more desirable to charge a simple isoparaffin such as 2-methylheptane or 2,4-dimethylhexane than a complex isoparaffin such as 2,2,4-trimethylpentane.

It will, of course, generally be impractical to charge any particular hydrocarbon in an absolutely pure state, especially when using higher-boiling hydrocarbons. When it is desired to produce particular individual paraffins in a relatively pure state, which can be readily purified by fractional distillation, the hydrocarbon mixture charged should be relatively free of readily reactive paraffins other than the one necessary to produce the desired product. When isoparaffins are reacted, the presence of limited amounts of normal paraffins is generally not deleterious, and may at times be advantageous in controlling the reaction. At other times, less pure hydrocarbon fractions may be used.

As previously mentioned, it is preferable to use either secondary or tertiary alkyl halides, and it is also preferable that the halides be chlorides. The alkyl halides having relatively low molecular weights are generally readily obtained in a more or less pure form, especially those having not more than about six carbon atoms per molecule. Especially when it is desired to produce a gasoline, such as aviation gasoline, or some certain valuable hydrocarbon or hydrocarbons boiling in the motor-fuel range, it will be desirable to use such a low-molecular-weight halide in a pure state. In any case in which such a particular hydrocarbon product is desired, the individual paraffin and alkyl halide suitable for forming it may be readily selected by trial, in the light of the present disclosure. At other times, a more or less impure alkyl halide fraction may be used.

The temperature, reaction time, and relative amount of sulfuric acid are interrelated. With higher temperatures and/or larger amounts of acid, shorter reaction times may be used. When it is desired to produce a relatively pure product, shorter reaction times and smaller yields per pass should be used, and when a certain appreciable amount of side reactions, or secondary reactions, may be tolerated, the process can be so operated as to have longer reaction times and higher yields per pass. The most desirable conditions in any particular instance can be readily determined by trial. When sulfuric acid strength in excess of 100 per cent is mentioned, reference is made to

so-called "fuming" sulfuric acid which, when titrated with an alkali, reacts with sufficient alkali to be equivalent to the amount of acid indicated.

The following examples are given for the purpose of illustrating a few of the many possible modes of operation of the process; they are not necessarily to be taken as establishing limitations of the invention.

Example I

To a mixture of 500 cc. of 96 per cent sulfuric acid and 359 grams of isobutane in a flask, which was equipped with a reflux condenser and a mercury-sealed motor-driven stirrer and which was cooled to about 10° F., was added 185 grams of tertiary butyl chloride during about half an hour. The reaction mixture was stirred vigorously during the addition and for about four hours thereafter; the temperature was kept below about 40° F. Considerable hydrogen chloride was evolved. On standing, the resultant mixture separated into an acid layer and into a hydrocarbon layer, which was removed and washed with dilute alkali. This hydrocarbon layer was completely paraffinic and had a substantial content of hydrocarbons having more than four carbon atoms per molecule.

Example II

To a mixture of 500 cc. of sulfuric acid having a strength of 102 per cent by weight and 288 grams of isopentane, in a flask fitted with a reflux condenser and with a motor-driven stirrer, was added 160 grams of isopropyl chloride during about half an hour. The reaction mixture was stirred vigorously during the addition and for about four and a half hours thereafter; the temperature was maintained at about 70° F. After the acid was separated from the resultant mixture by settling, the hydrocarbon layer was freed from acidic material by washing with dilute alkali, and then it was fractionally distilled. The material other than unreacted isopentane, and boiling from 85 to 410° F., amounted to 99 per cent by weight of the total hydrocarbon product and to 78 per cent by weight of the theoretical yield based on the formation of octane.

Example III

To a mixture of 500 cc. of 96 per cent sulfuric acid and 288 grams of isopentane, in a flask fitted with a reflux condenser and a motor-driven stirrer, was added 185 grams of tertiary butyl chloride during about an hour. The reaction mixture was stirred vigorously during the addition and for about four hours thereafter; the temperature was maintained at about 70° F. After the acid was separated from the resultant mixture by settling, the hydrocarbon layer was removed and freed from acidic material by washing with dilute alkali. Of the hydrocarbon material other than isopentane, 96 per cent by weight boiled between 85 and 410° F.; this fraction amounted to 83 per cent by weight of the theoretical yield based on the formation of nonane.

Example IV

To a mixture of 500 cc. of sulfuric acid having a strength of 102 per cent by weight and 288 grams of isopentane was added 185 grams of secondary butyl chloride during about an hour. The mixture was stirred vigorously during the addition and for about three hours thereafter; the temperature was maintained at 68° F. The sul-

furic acid was separated by settling, and the hydrocarbon layer was freed from acidic material by washing with alkali. Of the hydrocarbon material other than isopentane, 98 per cent by weight boiled between 85 and 410° F.; this fraction, which was completely paraffinic, amounted to 90 per cent by weight of the theoretical yield based on the formation of nonane.

Example V

To a mixture of 180 grams of isopentane and 500 cc. of sulfuric acid, which had a strength of 102 per cent by weight and which contained 2 per cent by weight of aluminum chloride, was added 98 grams of isopropyl chloride during about half an hour. The mixture was stirred vigorously during the addition and for about four hours thereafter; the temperature was maintained at 68° F. The sulfuric acid was separated by settling, and the hydrocarbon layer was washed with dilute alkali. Of the hydrocarbon material other than isopentane, 98 per cent by weight boiled between 85 and 410° F.; this fraction, which was completely paraffinic, amounted to 80 per cent by weight of the theoretical yield based on the formation of octane.

Example VI

To a mixture of 438 cc. of 102 per cent sulfuric acid and 158 grams of isopentane was added 89 grams of isopropyl chloride during about half an hour. The mixture was stirred vigorously during the addition and for about half an hour thereafter; the temperature of the reaction mixture was 68° F. The sulfuric acid was separated by settling, and the hydrocarbon layer was freed from acidic material by a caustic alkali wash. After depentanization, the product contained over 95 per cent of hydrocarbons boiling in the gasoline range, almost half boiling in the octane range. The yield of gasoline was 37 per cent of the theoretical yield of octane; this yield is relatively smaller than those obtained in the preceding examples because of the relatively short time of reaction.

Example VII

A liquid butane stream, comprising isobutane as the major constituent, is mixed with about one-third an equivalent volume of a material consisting principally of isopropyl chloride. The resultant mixture or blend is continuously and intimately admixed, by a mechanical mixing pump, with one-half the equivalent volume of sulfuric acid having a strength of about 101 per cent, and consisting of a blend of equal parts of fresh and recycled acid. The resultant liquid mixture, or emulsion, is rapidly passed through an elongated tube coil of restricted cross-sectional area, which is immersed in a liquid bath which removes heat and maintains the reaction temperature below 80° F. The turbulence set up by the rapid flow through the tube coil aids in maintaining an intimate mixture of the reactants. After a reaction time of about 10 minutes, the stream is passed to separating means, wherein the hydrocarbon material is separated from the sulfuric acid material and from hydrogen chloride. The free acid in the hydrocarbon material is neutralized and removed by an alkali wash, and the stream is then passed to a series of fractionators. In these fractionators there is separated a butane stream containing unreacted isobutane which is recycled, an alkyl halide

stream containing unreacted isopropyl chloride which is also recycled, and a hydrocarbon fraction boiling within the motor-fuel range and containing a high concentration of highly branched isoheptanes, such as 2,2,3-trimethylbutane and 2,4-dimethylpentane, which have very good anti-knock ratings. In order to prevent an accumulation of undesirable constituents, a portion of the butane stream and the alkyl halide stream may be removed from the system, or these streams may be subjected to further fractionation to produce streams having higher concentrations of the desirable constituents. The isoheptanes with high antiknock qualities are readily separated as a hydrocarbon fraction having a narrow boiling range and containing them in high concentration.

In view of many possible modifications of the process that will be obvious to those skilled in the art, the invention should not be limited unduly by the foregoing specification and examples, but it should be understood to be as extensive in scope and equivalents as defined in the appended claims.

I claim:

1. In a process for the production of paraffin hydrocarbons of relatively high molecular weight from paraffin hydrocarbons of lower molecular weight, the steps which comprise establishing an intimate admixture of an isoparaffin in liquid phase, an alkyl halide in the liquid phase, selected from the group consisting of secondary and tertiary alkyl halides and having not more than six carbon atoms per molecule, and sulfuric acid having a strength greater than 90 per cent by weight and containing between about 0.5 and 5 per cent by weight of aluminum sulfate as the catalyst, maintaining said intimate mixture at a suitable reaction temperature for a period of time sufficient to effect a reaction of isoparaffin and alkyl halide to form isoparaffins of high molecular weight, and subsequently separating from the reaction mixture a hydrocarbon fraction containing isoparaffins of high molecular weight so formed.

2. The process of claim 1 in which the alkyl halide is a tertiary alkyl halide.

3. The process of claim 1 in which the alkyl halide is an alkyl chloride.

4. The process of claim 1 in which the alkyl halide is an alkyl fluoride.

5. The process of claim 1 in which the alkyl halide is a secondary alkyl chloride and in which the strength of sulfuric acid is between 100 and 105 per cent by weight.

6. The process of claim 1 in which the sulfuric acid has a strength between 96 and 102 per cent by weight.

7. The process of claim 1 in which the sulfuric acid has admixed with it a portion of spent acid previously used in the process.

8. A process for the production of paraffin hydrocarbons of relatively high molecular weight from paraffin hydrocarbons of lower molecular weight, which comprises establishing an intimate admixture of an isoparaffin having not more than eight carbon atoms per molecule, an alkyl halide selected from the group consisting of secondary and tertiary alkyl halides and having not more than six carbon atoms per molecule, and sulfuric acid having a concentration greater than 95 per cent by weight and containing between

about 0.5 and 5 per cent by weight of aluminum sulfate as the catalyst, maintaining said intimate admixture at a reaction temperature not greater than about 125° F. for a period of time sufficient to effect reaction of alkyl halide with isoparaffin to form an isoparaffin of high molecular weight with elision of the corresponding hydrogen halide, and subsequently removing from the reaction products a hydrocarbon fraction containing isoparaffins of high molecular weight so produced.

9. A process for the production of isoheptanes having a high antiknock rating, which comprises establishing an intimate admixture of isobutane, isopropyl chloride, and sulfuric acid having a concentration greater than 95 per cent by weight and containing between about 0.5 and 5 per cent by weight of aluminum sulfate as the catalyst, maintaining said intimate admixture at a reaction temperature not greater than about 125° F. for a period of time sufficient to effect reaction of isopropyl chloride with isobutane to form isoheptanes with elision of hydrogen chloride, and subsequently removing from the reaction products a hydrocarbon fraction containing isoheptanes so produced.

10. A process for the production of isoparaffin hydrocarbons of relatively high molecular weight from isoparaffin hydrocarbons of relatively low molecular weight, which comprises establishing an intimate admixture of an isoparaffin having not more than eight carbon atoms per molecule, an alkyl halide selected from the group consisting of secondary and tertiary alkyl halides and having not more than six carbon atoms per molecule and sulfuric acid having a concentration greater than 95 per cent by weight and containing between about 0.5 and 5 per cent by weight of aluminum sulfate as the catalyst, maintaining said intimate admixture at a temperature not greater than about 125° F. for a period of time sufficient to effect an alkylation reaction between alkyl halide and isoparaffin to form isoparaffins of higher molecular weight, subjecting the reaction effluent which comprises unreacted reactants, sulfuric acid and reaction products to a separating means to separate sulfuric acid and hydrogen halide, passing at least a portion of said sulfuric acid to admixture with the incoming charge stock to the reactor, subjecting the remaining 50 predominantly hydrocarbon portion of the reaction effluent to a treatment with alkali to remove acidic material, passing alkali treated hydrocarbon reaction effluent to fractionating means to separate said effluent into a fraction containing isoparaffins in the motor fuel range and a light hydrocarbon fraction, recycling a portion of said light hydrocarbon fraction to said alkylation reaction, and subsequently removing the fraction containing motor-fuel range isoparaffins of higher molecular weight from the process.

11. In a process of alkylating paraffins to form other paraffins of higher molecular weight, the step which comprises inter-reacting an alkylatable paraffin hydrocarbon and an alkyl halide in the presence of concentrated sulfuric acid containing between about 0.5 and 5 per cent by weight of aluminum sulfate as the alkylating catalyst to form a paraffin hydrocarbon of higher molecular weight.

FREDERICK E. FREY.
